UNITED STATES PATENT OFFICE.

NEWTON I. SMITH, OF ALTOONA, PENNSYLVANIA.

CLAMP FOR ELECTRIC CONDUCTORS.

Application filed August 4, 1928. Serial No. 297,477.

The invention relates to certain new and useful improvements in snap clamps for electric conductors, such as commonly employed for connecting transmission lines, 5 bus-bars and the like with the ground or with electric motors or other translating devices, and has for its object to provide a simple and effective device that may be quickly applied to the conductor in any and 10 all positions of the latter with the assurance of an effective electrical contact between the clamp and the conductor.

The invention is illustrated in the accompanying drawings, in which:

- 15 Fig. 1 is a perspective of the device.
Fig. 2 is a front elevation of the upper portion of the clamp and its supporting rod.
Fig. 3 is a side elevation thereof.
Fig. 4 is a plan view.
20 Referring to the drawings, 1 indicates a head section formed of a casting of brass or other suitable metal having a flat face 3 provided with a tongue 4 forming an extension of said flat face and terminating in 25 the beveled end 5. The side of the head opposite the flat face is provided with a clamping seat 2 adapted to receive the end of a cable or similar conductor 18, which is secured by a clamping plate 16 traversed by a 30 set screw 17. In order to firmly affix the end of the cable to the head, the cooperating faces of the seat 2 and the clamping plate 16 are provided with U-shaped grooves into 35 which the bent end of the cable or conductor is fitted.

The lower end of the head 1 is provided with a socket 6 adapted to receive the end of a rod or pole 20 by means of which the clamp is applied to and removed from the 40 conductor, the tongue 4 forming an extension of the flat face of the head engaging the rod in the manner illustrated in Figs. 1 and 3. The upper end of the head is provided with perforated ears 7 in which is 45 pivotally mounted a jaw member 10, by means of cross pin 12 engaging registering openings in the ears 7 and the upper end of the jaw 10. The said jaw 10 is of generally blade-like form having an inner edge or 50 face which normally engages the flat face 3 and extension tongue 4 of the head substantially throughout the length of these latter elements, and, if desired, this face or edge of the jaw may be provided with spaced 55 notches adapted to engage conductors to

hold the same firmly clamped between the jaw and the head. The end of the jaw opposite the pivotal connection is flared or curved at 11 in order to permit the jaw to be readily slipped over a conductor, which latter is guided into the throat between the jaw and the head.

The jaw 10 is provided with lateral lugs 13, which are perforated and which lie opposite similar lugs 9 formed on the head 1, the corresponding lugs 13 and 9 on the jaw and head, respectively, being traversed by bolts 14 carrying helical springs 15 which serve to draw the jaw 10 firmly into engagement with the flat face 3 and tongue 4 of the head.

It will be understood that the conductor or cable 18 and the supporting rod 20 may be of any desired length, and the free end of the cable 18 is provided with a suitable 75 connector, such as 21, by means of which the clamp may be electrically connected with the grounding means or with another conductor, as will be understood.

It will be particularly noted that the 80 clamp is free from projecting parts which would tend to obstruct the entrance of a conductor of any type, such as an overhead wire or a stationary bus-bar, between the jaw and head portion, that the relation of 85 the jaw and the cooperating face of the head and the tongue extension thereof insures an effective electric connection between the conductor, whatever the size of the latter, and the head. In applying the clamp to the 90 conductor, the curved end of the jaw 10 is hooked over the conductor and the clamp moved by the pole 20 to cause the conductor to enter the throat between the jaw 10 and the flat face of the head, the entrance being 95 facilitated by the beveled end of the tongue 4 and the curved end of the jaw. The relatively large zone of engagement between the jaw and the head insures a firm clamping of 100 the conductor between the jaw and the head whether the conductor be a relatively small wire or a heavy bus-bar. Likewise the location of the conducting cable on the side of the head opposite that of the clamping jaw prevents the cable offering any obstruction to the engagement between the clamp 105 and the conductor.

What I claim is:

A clamp for electric conductors comprising a metal head having a flat lateral face 110

with a tongue forming a longitudinal extension thereof and a socket in one end to receive a supporting rod, a jaw pivoted to the upper end of the head having a face normally engaging the flat face and tongue of the head substantially throughout the length thereof and terminating in a flared end,

spring means for forcing the jaw toward the head, means on the side of the head opposite the jaw for securing a flexible conductor to the head, and a rod engaging the socket in the head. ¹⁰

In testimony whereof, I affix my signature.
NEWTON I. SMITH.
